[57] CLAIM

The ornamental design for a purse holding hook, substantially as shown and described.

DESCRIPTION

FIG. 1 is a left side elevational view of a purse holding hook showing my new design;

FIG. 2 is a rear elevational view thereof;

FIG. 3 is a front elevational view thereof;

FIG. 4 is a top plan view thereof;

FIG. 5 is a bottom plan view thereof; and

FIG. 6 is a left side elevational view of an alternate embodiment of the design for a purse holding hook.
